DESIGN FOR AN AIRPLANE CONTROL WHEEL

Theodore Obszarny, Chicago, and John J. Rowell,
Prospect Heights, Ill., assignors to Guardian
Electric Manufacturing Co., Chicago, Ill., a cor-
poration of Illinois

Application November 17, 1942, Serial No. 108,796

Term of patent 14 years

To all whom it may concern:

Be it known that we, Theodore Obszarny and John J. Rowell, both citizens of the United States and residents, respectively, of Chicago and Prospect Heights, in the county of Cook and State of Illinois, have invented a new, original, and ornamental Design for an Airplane Control Wheel, of which the following is a specification, reference being had to the accompanying drawings forming a part thereto,

Figure 1 is a top plan view of an airplane control wheel embodying our novel design;
Figure 2 is a front elevational view thereof;
Figure 3 is a side elevational view thereof; and
Figure 4 is a perspective view thereof.

We claim:

The ornamental design for an airplane control wheel, substantially as shown.

THEODORE OBSZARNY.
JOHN J. ROWELL,
